UNITED STATES PATENT OFFICE.

WILHELM GUTZEIT, OF CHARLOTTENBURG, GERMANY.

MANUFACTURED PLATE FOR CEILING CONSTRUCTIONS.

SPECIFICATION forming part of Letters Patent No. 756,015, dated March 29, 1904.

Application filed April 11, 1903. Serial No. 152,124. (No model.)

To all whom it may concern:

Be it known that I, WILHELM GUTZEIT, a subject of the King of Prussia, German Emperor, and a resident of Charlottenburg, in the Kingdom of Prussia, Germany, have invented certain new and useful Improvements in Manufactured Plates for Ceiling Constructions, of which the following is a specification.

This invention has reference to plates for the construction of ceilings manufactured from an artificial composition. These plates may be made with or without iron cores or wire-netting embedded therein.

The invention consists particularly in producing plates of such character that by their insertion between the beams or girders a ceiling is obtained which sustains heavy weight. At the same time the upper portion of the ceiling forms a finished floor without requiring any covering material—such as asphalt, linoleum, boarding, or the like—and a floor is directly obtained which may be polished or painted and permits of driving nails therein. On the lower surface the plates have transversal ribs at short intervals, which likewise permit of driving nails therein. The transversal ribs enable one to put on directly the plastering, to mount gas-piping and electrical wires, and to fasten partitions of planks or of plastered wire-cloth. To attain this purpose, the plates are manufactured of material which permits of driving nails therein. They are formed in such a manner that sustaining-ribs extend from the horizontal upper slab portion, which is level on the top, down to the lower plane of the girder-flanges.

Transportable plates for ceiling constructions are well known. Heretofore other ceilings were constructed with beams of material permitting of driving nails therein. These beams were inserted between the girders and placed edgewise. Other ceilings were made of beton and iron cores embedded therein. The plates of these are in form of caps with a level upper portion from which ribs extend downwardly. These ceilings are deficient, because they lack the advantageous effect of the combination of a plate material permitting of driving nails therein with the form of ribbed caps or slabs. Besides, they

are not easily manufactured for insertion. Other ceilings with beams permitting of nailing do not produce a finished floor, and their capacity of sustaining weight is less, not to mention the troublesome, time-wasting, and costly mounting of the single beams in their reciprocal location. Further, ceilings made before were provided with ribs, which increase the durability; but they require a separate floor on top, and on the lower surface wooden rafters must be provided for fixing the plastering and the like.

The present invention produces ceilings in which the described deficiencies are avoided. The plates of which the ceilings are composed possess the advantage of being easily inserted, and they are plain in construction and quickly manufactured. There is an increased guarantee for the uniformity of the plate material, because it is manufactured in special works. The advantageous arrangement of the ribs increases the capacity of sustaining weight, and the ability of driving nails into this material is not to be considered alone. The fact that the plates from this material are made in the form of caps or slabs with ribs reaching to the lower plane of the girder-flanges, said form being well known in beton-iron ceilings, develops the useful property of the material—viz., to drive nails therein. In addition there is the beneficial effect of obtaining directly a finished floor by uniting the plates to form the ceiling, which floor may be painted and nailed and which has below a set of ribs forming a level lower surface and serves for the direct fastening of the plastering, gas-pipes, other pipes, intermediate walls, &c. From this advantageous combination and arrangement results a substantial saving in the various detail work of finishing the ceiling, and thereby time, material, and wages are saved. The form of ceiling illustrated in the drawings further shows an additional advantage. There is an arrangement of a tenon and mortise on the sides of the upper portion of the plates. This appliance does not solely serve for the purpose of obtaining the desired joint that is a well-fixed assemblage of the plates which are set against each other. It also forces the workingman to insert the plates properly be-

fore the masonry-work at the ends of the beams is done, because otherwise the tenon-and-mortise device will not join. This is necessary for a quick production of the ceiling 5 and the early use of the latter for storing material, the erection of scaffolding, &c.

In the drawings, Figure 1 represents a plate in longitudinal section. Fig. 2 is a cross-section of same. Fig. 3 shows the plate in front 10 view. Fig. 4 represents a plate in longitudinal elevation. Fig. 5 is a bottom view, and Fig. 6 illustrates in perspective view a part of the ceiling composed of the plates.

In carrying out my invention I construct 15 plates or tiles which are composed of turf, slag, rubbish, wood, slag, and quicklime, and an organic binder, such as molasses. When these ingredients are thoroughly mixed and made into a pasty mass of the proper consistency, the tiles may be molded by hydraulic 20 pressure and are then quickly dried, and the product is a fireproof tile which does not warp and which is penetrable to the extent that nails or screws and the like may be driven 25 therein, and although these tiles are plastic they may be cut or worked like wood.

In forming a tile the upper surface thereof is made flat to provide a slab portion *a*, which forms a floor when the plates are assembled, 30 and around the edges of this slab portion are formed mortise-and-tenonconnections *g*, which interlock upon the contiguous edges of the slab portion when the plates are assembled, and thus the use of mortar or cement to fill in 35 the interstices of the joints is obviated. Extending transversely from the lower side of the slab portion *a* are ribs *d*, which may be arranged at each side and in the middle, as shown in the drawings. These ribs not only 40 strengthen the tile, but provide a foundation for securing a plastering-base, such as wire-netting, laths, or the like. To further strengthen the tiles, the ribs *d* may have metal 45 cores *b* or wire-netting embedded therein, as shown in Figs. 2 and 6. The ends of the plates are formed with projections *c*, which are adapted to engage between the flanges of the girders *h* and the height of which is such as to permit the tiles or plates to be used with 50 girders of various heights, and these projections terminate short of the upper and lower surface of the tile, so that a groove is formed between the upper slab portion *a* and the projections *c*, which permits the upper slab portion 55 to project or overlap the edge of the upper flange of the girder and contact with the adjacent tile. At the ends along the lower edge there is formed a rabbet *c'*, which fits upon the lower flange of the girders and by 60 means of which the lower edges of the ribs *d* are caused to lie flush with the end face of the girders, so that when the plastering-base *f* is secured thereto the lower flanges of the girders do not offer obstructions to the same, and 65 a level ceiling is insured.

By forming the plates in the manner above described a combined floor and ceiling construction is provided, and the plates may be inserted between the girders without the use of false supporting-work beneath. 70

It being premised that the girders have been placed upon the walls of a building under construction, the plates are slid in between the girders and preferably arranged so that one series of plates will break joint 75 with those of another series, as is shown in Fig. 6, and by means of the mortise-and-tenon connection they are securely locked together, and this locking is insured by reason of the fact that the plates have to be in intimate 80 contact before the wall at the end of the girders is built above the girders; otherwise the plates could not be inserted and any opening between the plates could not afterward be made up. 85

Having thus described my invention, what I claim, and desire to secure by Letters Patent, is—

1. In a combined floor and ceiling construction, the combination with the beams or girders, of tiles supported by the girders and each having an upper slab portion forming a floor-surface, the ends of the slab portion overlapping the tops of the girders, and means formed on the contiguous edges of the slab portions 95 to lock the tiles together.

2. In a combined floor and ceiling construction, the combination with the beams, of tiles supported by the beams and each having an upper slab portion forming a floor-surface, the 100 ends of the slab portion overlapping the tops of the girders, means formed on the contiguous edges to lock the tiles together, and ribs extending from the lower face of the slab portion 105 and having their edges flush with the under face of the beams.

3. In a combined floor and ceiling construction, the combination with the I-beams, of tiles composed of penetrable plastic material supported by the beams and each having an upper slab portion forming a floor-surface, the ends of the slab portion overlapping the tops of the girders and having their contiguous edges interlocked, ribs extending from the lower face of the slab portion, projections 115 formed on the ends of the tiles and adapted to engage the lower flange of the beams and having their lower edges rabbeted to correspond with the thickness of said lower flange, whereby the edges of the ribs are flush with the under face of the beams. 120

4. In a combined floor and ceiling construction, the combination with the I-beams, of tiles composed of penetrable plastic material, and each having an upper slab portion, the ends of 125 which overlap the top of the beams to form a floor-surface, ribs projecting from the lower face of the slab portion, projections formed on the ends of the tiles terminated short of the upper surface thereof and having a rabbet 130

formed in their lower edges, the projections extending between the upper and lower flanges of the beams with the rabbets engaging the lower flange, whereby the edges of the rabbets are flush with the under face of the beams, and a plastering-base secured to the edges of the ribs, substantially as specified.

5. In a combined floor and ceiling construction, the combination with the I-beams, of tiles 10 composed of penetrable plastic material and each having an upper slab portion forming a floor-surface, tenon-and-mortise connections on the contiguous edges of the slab portion, projections on the ends of the tile terminated

short of the upper and lower surfaces thereof 15 and adapted to extend between the upper and lower flanges of the beams, whereby the ends of the slab portion will overlap the upper surface of the beams and the lower surface of the tiles will lie flush with the under face of the 20 beams, substantially as specified.

Signed at Berlin this 27th day of March, 1903.

WILHELM GUTZEIT.
